CLAIM

The ornamental design for a nozzle for dispensing gases as shown and described.

DESCRIPTION

FIG. 1 is a first side view of a first nozzle for dispensing gases.

FIG. 2 is a second side view of a first nozzle for dispensing gases.

FIG. 3 is a top plan view of a first nozzle for dispensing gases.

FIG. 4 is a bottom plan view of a first nozzle for dispensing gases.

FIG. 5 is a front side view of a first nozzle for dispensing gases.

FIG. 6 is a backside view of a first nozzle for dispensing gases; and,

FIG. 7 is an isometric view of a first nozzle for dispensing gases.

The broken lines of FIGS. 5 and 6 are for the purpose of illustrating the nozzle for dispensing gases and form no part of the claimed design.

1 Claim, 7 Drawing Sheets
